COMBINED SHOE RACK AND TREE

Merritt W. Gano, Jr., Denver, Colo.

Application May 17, 1941, Serial No. 393,875

9 Claims. (Cl. 12—129.1)

This invention relates, generally, to racks and similar devices, and it has particular relation to a combined shoe rack and tree.

One of the main objects of the invention is to provide a combined shoe rack and tree for supporting shoes of varying size, shape, or style, and operable to shape and maintain the shape of the shoe when in supported position on the rack.

Another object of the invention is to provide a combined shoe rack and tree of simple and inexpensive construction, and which may be readily attached, for example, to the inside of a closet door, or to a wall or other structure; also a combined shoe rack and tree which is easy to manipulate and which effectively accomplishes the desired results.

Another object of the invention is to provide a combined shoe rack and tree which is readily adjustable to cover the entire range of shoe sizes; also a combined shoe rack and tree the features of which are adapted for use with women's shoes as well as with men's shoes, and a shoe rack and tree which may be of a character to support a plurality of pairs of shoes or any desired number of shoes.

While the particular structural features and combinations by which I obtain a combined shoe rack and tree of the character set forth are important features within the more specific aspects of the invention, it is to be understood that the precise features shown and described may be varied within the broader aspects of the invention.

In order to acquaint those skilled in the art with the construction and operation of a combined shoe rack and tree embodying the present invention I will now describe, in connection with the drawings, certain preferred embodiments of the invention.

In the drawings:

Figure 1 is a front elevational view partially broken away and showing a combined shoe rack and tree embodying the present invention;

Figure 2 is an end view of the combined shoe rack and tree, looking from the right hand end as the device is viewed in Figure 1;

Figure 3 is a vertical section taken on the line 3—3 of Figure 1;

Figure 4 is a detail section taken on the line 4—4 of Figure 1;

Figure 5 is a detail section taken on the line 5—5 of Figure 1, to show one suitable form of mounting for the adjustable base for the heel clamp;

Figure 6 is a fragmentary rear elevational view taken on the line 6—6 of Figure 5 and showing the adjustable mounting for the base for the heel clamp;

5 Figure 7 is a view similar to Figure 2, showing a modified form of the combined shoe rack and tree for use with women's shoes;

Figure 8 is a vertical section taken on the line 8—8 of Figure 9; and

Figure 9 is a fragmentary front elevational view of the device shown in Figure 7.

Referring first to Figures 1 to 6, inclusive, of the drawings, the embodiment of the invention shown in these figures comprises a frame 10 consisting of parallel upper and lower frame members 11 and 12 and parallel end frame members 13 and 14 welded, riveted, or otherwise suitably joined to the frame members 11 and 12. The frame members are shown as of angle section, but this may vary, and it is to be understood that frames of other shapes or configurations may be employed within the scope of the present invention.

The frame 10 has openings, for example, at 15 through which the shanks of screws 16 or other fastening means are adapted to pass for securing the frame, for example, to the inside of a closet door, indicated fragmentarily at 18 in Figure 2, or to a wall or other structure. The frame 10 shown in Figure 1 is adapted to support two pairs of men's shoes, but it is to be understood that the device may be adapted to support any other desired number of shoes.

Two parallel upright members 20 are provided 35 for each shoe, one shoe being indicated at 21 in Figures 1 and 2. The opposite ends of the members 20 are welded, riveted, or otherwise suitably secured to the upper and lower frame members 11 and 12.

40 Attached to the bottom frame member 12 are a plurality of toe hold clamps 25 one disposed across the lower ends of each pair of upright members 20. These toe hold clamps 25 may be in the form of angle members, the flanges 26 of 45 which are adapted to engage over the tip of the sole of the shoe as shown. While the toe hold clamps or sole clips 25 may be fixed within the scope of the present invention, I prefer to make the same adjustable toward and away from the frame 10. This may be accomplished, for example, by screws 27 fixed in the frame member 10, the shanks of the screws having threaded engagement with lugs 28 at the opposite ends of the sole clips, and the outer ends of the screws 50 having finger pieces 30 by means of which the

screws may be manipulated to adjust the sole clips toward and away from, or substantially normal to the frame member 12. Some men's shoes are lasted on lasts that leave a slight curve or "rocker" in the sole. By having the sole clips adjustable as set forth, any kind of treeing desired may be had.

Adjustable along the uprights 20 toward and away from or substantially normal to the toe hold clamps 25 are the heel clamps, each indicated in its entirety at 35. Each of the heel clamps 35 comprises a base member 36 carrying an outwardly extending post 37. Generally U-shaped heel clamp rods 38 have first legs 39 slidable axially, and adapted, if desired, to turn in the posts 37. Each rod 38 also has a second leg 40 adapted to enter the shoe 21 at the heel thereof, and to clamp the heel of the shoe against the frame 10, and particularly against the upright members 20 of the frame. Head members 42, which may be formed of a plastic material or any other material and which may, if desired, be padded, are secured on the free ends of the legs 40 of the rods 38 for cooperation with the interior of the shoe at the heel, as shown.

The base members 36 are carried by transverse angle pieces 45 slotted at 46 (Figure 5) for sliding movement along the upright members 20 and to be guided by these members. The outer portions of the slotted parts of the angle pieces 45, which are shown in Figure 1, may be of spring character for the purpose of frictionally engaging the cooperating flanges of the upright members 20 to hold the heel clamps 35 in any adjusted position. Another manner of accomplishing this frictional retention for holding the heel clamps in adjusted position is to form the flanges 47 of the angle pieces 45 with inturned spring extensions 48 for cooperation with the adjacent flanges 49 of the upright members 20 as shown in detail in Figures 5 and 6. The extent of adjusting movement of the heel clamps 35 along the upright members 20 is preferably sufficient to cover the entire range of shoe sizes.

The heel clamp rods 38 are tensioned by springs disposed along the legs 39 of the rods. In Figures 1, 2, and 3, these springs are shown in the form of coiled springs 50 surrounding the posts 37 and anchored at one end at 51 to the base 36 and turned at the other end at 52 into an opening in the leg 39 of the rod 38. The contracting springs 50 maintain the rods 38 yieldingly in clamping position, and return the same to such position to clamp the shoes in place at the heels thereof. The legs 39 of the rods 38 are preferably adapted to turn in the posts 37 to permit swinging the clamping legs 40 with the head members 42 thereon to the right or to the left of the positions shown in Figure 1 to clear the heel of the shoe for facilitating mounting the shoe on the rack. With the springs 50 arranged as shown in Figures 1, 2, and 3, these springs, in addition to setting up the desired shoe clamping tension, also return the rods, and particularly the clamping legs 40 thereof, to the positions shown in Figure 1 for entry into the shoe at the heel thereof.

In the embodiment shown in Figure 8, the coiled tensioning spring 50', which corresponds with the spring 50 of Figure 3, is housed within the holder or post 37' for the leg 39' of the clamping rod 38'. In this case the spring 50' is an expanding spring interposed between the flanged outer end 53 of the post or holder 37' and an abutment or head member 57 on the inner end

of the leg 39' of the rod 38'. The head member 57 is threaded or otherwise detachably mounted on the inner end of the leg 39' of the clamping rod to facilitate assembly, and stop means, such as a cap screw 58, is threaded or otherwise removably secured in the inner end of the holder or post 37' to limit the inward movement of the clamping rod under the action of the spring 50'. The spring 50' acts yieldingly to urge the head member 42' on the free end of the second leg of the clamping rod toward the frame for the purpose of clamping the heel of the shoe against the frame to shape and maintain the shape of the shoe when in supported position, as in the other embodiment of the invention. The other parts in Figures 7, 8, and 9, corresponding with parts of the other embodiment of the invention, are indicated by primed reference characters corresponding with the reference characters in the other figures.

In the case of women's shoes, as indicated by the shoe 21' in Figure 7, lined toe caps 60 are preferably provided for receiving and holding the toes of the shoes instead of the sole clips 25. The caps 60 may be lined with felt or other suitable material at 62 so as not to injure the toe of the shoe. It will be noted that the cap 60 engages the exterior of the toe of the shoe, and that the toe clip 25 for men's shoes also engages the exterior of the shoe. The toe caps 60 may be adjustable toward and from the frame 10' in the manner in which the toe clips 25 are adjustable, although such adjustment for the toe caps of women's shoes is usually not required because of the adaptability of these toe caps for cooperation with the toes of women's shoes of varying shapes and styles.

In order to take care of heels of different heights and, particularly, to take care of both high and low heels of women's shoes, I provide means for adjusting the heel clamp rod 38'. This may be accomplished, for example, by making the leg 40' of the heel clamp rod 38' relatively short, and providing detachable sections 65 of different lengths, each provided with its clamping head or button 42'. These detachable sections 65 may be interchangeably connected to the short legs 40' of the heel clamp rods, for example, by engagement of a pin 66 carried by the detachable rod section 65 in a bayonet slot 67 in a sleeve or ferrule 68 attached to the short leg 40' of the rod, or in any other suitable manner. A spring 70 may be provided yieldingly to hold the pin 66 interlocked with the inner end of the bayonet slot 67.

Where the inner or lower ends of the heels of women's shoes are too small to be clamped against the uprights corresponding with the uprights 20 of the frame as in the case of men's shoes, the rack for women's shoes may have a heel plate 72 secured to the base or carriage 36' and adjustable therewith. This heel plate 72 may, if desired, have lugs 74 engaging the adjacent flanges of the upright members 20 to guide the heel plate in its adjusting movement along the upright members 20' with the base or carriage 36'.

In the use of the rack, the heel clamp rod is grasped, for example, along the intermediate portion which constitutes a suitable handle, and the rod is pulled out against the action of the spring sufficiently to clear the heel clamp button 42 or 42' of the heel of the shoe. The shoe is then placed in position as shown in Figures 1, 2, and 7—in the case of a man's shoe, with the tip

of the sole 76 of the shoe engaging the flange 26 of the sole clip 25, and, in the case of a woman's shoe, with the toe of the shoe engaging in the toe cap 60.

Where the side is clear so that the heel of the shoe may be placed in position in a sidewise direction, all that is required is to pull the heel clamp rod out sufficiently to permit the shoe to be placed in position. If the side is not clear, for example, because other shoes are in place on the rack, the leg 40, for example, of the rod 38 of the rack for men's shoes, or the corresponding leg 40' of the rod 38' of the rack for women's shoes may be swung to the left or to the right from the positions shown in Figures 1 and 9 sufficiently to clear the heel of the shoe.

Upon arranging the shoe in place and in engagement with the toe clip or toe cap and positioning or allowing the heel clamp rod to assume position for entry into the shoe at the heel thereof as shown in Figures 1 and 9, the heel clamp rod is released and the spring 50 or 50' moves the heel clamp rod toward the frame of the rack, causing the heel clamp head or button 42 or 42' to engage within the heel of the shoe and to clamp the heel of the shoe against the upright members 20 of the frame 10, or against the plate 12 of the frame 10'. The spring tension thereby shapes and maintains the shape of the shoe when in supported position on the rack.

The embodiments of the invention shown in the drawings are for illustrative purposes only, and it is to be expressly understood that said drawings and the accompanying specification are not to be construed as a definition of the limits or scope of the invention, reference being had to the appended claims for that purpose.

I claim:

1. A combined shoe rack and tree comprising a frame adapted for attachment to a support, a toe hold clamp for receiving and externally engaging the toe end of a supported shoe, and a heel clamp adjustable on said frame toward and away from said toe hold clamp to cover the desired range of shoe sizes and comprising a spring-tensioned heel clamp member adapted to enter the shoe at the heel thereof and to clamp the heel of the shoe against the frame to shape and maintain the shape of the shoe when in supported position.

2. A combined shoe rack and tree comprising a frame, a toe hold clamp for receiving and externally engaging the toe end of a supported shoe, a base member for a heel clamp adjustable on said frame toward and away from said toe hold clamp to cover the desired range of shoe sizes, a generally U-shaped heel clamp member having a first leg supported on said adjustable base member and a second leg adapted to enter the shoe at the heel thereof and to clamp the heel of the shoe against the frame to shape and maintain the shape of the shoe when in supported position, and spring means cooperating with the first leg of said heel clamp member for yieldingly maintaining the other leg of said heel clamp member in position clamping the heel of the shoe against said frame.

3. A combined shoe rack and tree comprising a frame, a toe hold clamp for receiving and externally engaging the toe end of a supported shoe, a heel clamp holder adjustable on said frame toward and away from said toe hold clamp to cover the desired range of shoe sizes, a generally U-shaped heel clamp member having a first leg extending into said heel clamp holder and a sec-

ond leg adapted to enter the shoe at the heel thereof, a head member on the free end of said second leg for clamping the heel of the shoe against the frame to shape and maintain the shape of the shoe when in supported position, and an expanding spring within said heel clamp holder and cooperable with the first leg of said heel clamp member yieldingly to urge the head member on the free end of the second leg of said heel clamp member toward the frame.

4. A combined shoe rack and tree comprising a frame, a toe hold clamp for receiving and externally engaging the toe end of a supported shoe, a base member for a heel clamp adjustable on said frame toward and away from said toe hold clamp to cover the desired range of shoe sizes, a generally U-shaped heel clamp member having a first leg supported for turning movement on one of said adjustable base member and a second leg adapted to enter the shoe at the heel thereof, a head member on the free end of said second leg for clamping the heel of the shoe against the frame to shape and maintain the shape of the shoe when in supported position, and spring means cooperating with the first leg of said heel clamp member for yieldingly maintaining the other leg of said heel clamp member in position clamping the heel of the shoe against said frame, said spring means also maintaining said head member in position to enter the shoe at the heel thereof and returning said member to such position where it is swung therefrom by turning of said first leg on said base member.

5. A combined shoe rack and tree comprising a frame, a toe hold clamp for receiving and externally engaging the toe end of a supported shoe, a base member for a heel clamp adjustable on said frame toward and away from said toe hold clamp to cover the desired range of shoe sizes, a generally U-shaped heel clamp member having a first leg supported on said adjustable base member and a second leg adapted to enter the shoe at the heel thereof and to clamp the heel of the shoe against the frame to shape and maintain the shape of the shoe when in supported position, spring means cooperating with the first leg of said heel clamp member for yieldingly maintaining the other leg of said heel clamp member in position clamping the heel of the shoe against said frame, and means for adjusting the lengths of said heel clamp member for heels of different height.

6. A combined shoe rack and tree comprising a frame, a toe hold clamp for receiving and externally engaging the toe end of a supported shoe, a heel clamp adjustable on said frame toward and away from said toe hold clamp to cover the desired range of shoe sizes and comprising a spring-tensioned heel clamp member adapted to enter the shoe at the heel thereof and to clamp the heel of the shoe against the frame to shape and maintain the shape of the shoe in supported position, and means for adjusting said toe hold clamp toward and away from said frame substantially normal to the plane of adjustment of said heel clamp.

7. A combined shoe rack and tree comprising a frame adapted for attachment to a support, a toe hold clamp for receiving and externally engaging the toe end of a supported shoe, a heel clamp adjustable on said frame toward and away from said toe hold clamp to cover the desired range of shoe sizes and comprising a spring-tensioned heel clamp member adapted to enter the shoe at the heel thereof and to clamp the

heel of the shoe against the frame to shape and maintain the shape of the shoe when in supported position, means for adjusting said toe hold clamp toward and away from said frame substantially normal to the plane of adjustment of said heel clamp, and means for adjusting the heel clamp for heels of different height.

8. A combined shoe rack and tree comprising a frame, a toe hold clamp for engaging the toe end of the sole of the shoe externally of the shoe and a heel clamp adjustable on said frame toward and away from said toe hold clamp to cover the desired range of shoe sizes and comprising a spring tensioned heel clamp member adapted to enter the shoe at the heel thereof and to clamp the heel of the shoe against the frame to shape and maintain the shape of the shoe when in supported position.

9. A combined shoe rack and tree comprising a frame, a toe clamp mounted on said frame and

adapted to receive and externally engage the toe of the shoe to hold the same to the frame, a heel clamp carriage mounted on said frame for sliding movement toward and away from said toe clamp, a generally U-shaped heel clamp member having a first leg and a second leg adapted to enter the shoe at the heel thereof to clamp the heel of the shoe to the frame, said first leg being mounted on said heel clamp carriage for sliding movement in a direction generally normal to the path of sliding movement of said heel clamp carriage and for turning movement to permit swinging said second leg laterally to position clear of the shoe upon withdrawing the heel clamp from clamping position, and spring means cooperating with said first leg yieldingly to maintain said second leg in position clamping the heel of the shoe to the frame and adapted to return said second leg to said position.

MERRITT W. GANO, JR.
